STARTING DEVICE, COMPRESSION RELIEF WITH AUTOMATIC LOCK RELEASE

James F. Wright, Upper Montclair, N. J.

Application November 20, 1945, Serial No. 629,742

2 Claims. (Cl. 123—182)

1

The invention relates to a lock release device, and more especially to a starting device, compression relief with automatic lock release or the like.

The primary object of the invention is the provision of a device of this character, wherein an exhaust valve of the engine is held open by a cam, which is operated, either mechanically or hydraulically from a pilot-pit or otherwise, so that any oil or excess gasoline can be forced out of the combustion chamber, into the exhaust system, thus a pilot can release the exhaust valve in the lower or inverted cylinder or cylinders, for turning the engine over with the starter and exhaust liquid, then turn on ignition, to effect a take-off of the craft, without damage to the engine.

Another object of the invention is the provision of a device of this character, wherein the spinning of the propeller by hand for the starting of the engine is eliminated, and damage to the latter is avoided through the presence of liquid within the cylinders of such engine resultant in a liquid lock therein, the device being of novel construction and is unique in its purpose.

A further object of the invention is the provision of a device of this character, which is simple in construction, thoroughly reliable and efficient in operation, readily and easily controlled and operated, possessed of few parts, strong, durable, and inexpensive to manufacture and install.

With these and other objects in view, the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings:

Figure 1 is a fragmentary side elevation of an aircraft radial cylinder engine, showing the device constructed in accordance with the invention applied and in one position.

Figure 2 is a top plan view, partly broken away.

Figure 3 is a view similar to Figure 1, partly broken away, and showing the device in a releasing position.

Figure 4 is a schematic outline of an aircraft with the device partly in elevation and partly in section in working position therein.

Similar reference characters indicate corresponding parts throughout the several views in the drawings.

Referring to the drawings in detail, the aircraft A which may be of any standard construc-

2

tion, has equipped therewith the usual power engine, one of its cylinders being denoted at 10, the exhaust valve therefor at 11, and the valve rocker at 12, respectively, these adjuncts being of the ordinary well-known construction and in arrangement thereof. The liquid lock release device constituting the present invention will be hereinafter fully described.

The liquid lock release device in accordance with the invention comprises, a release lever 13 mounted or straddling the exhaust valve rocker box 14, it being supported to extend through the rocker box cover 15 and by a pivot 16, has connection with a crank arm 17 fixed to the stub shaft 18 of a vertically swinging cam 19, which is adapted for pressing upon the roller contact 20 of the valve rocker 12 when operating in one direction, for opening the valve 11, and thus release the liquid lock within the cylinder 10. The lever or plunger 13 is operated through pivotal connection 21 with a bell-crank 22, swingingly supported at 23 without the rocker box 14, as best seen in Figure 2 of the drawings.

The bell-crank 22 is pivoted at 24 to a throw pitman 25 having break-joint connection 26 with the stem of a piston 27 within a hydraulic cylinder 28, its fluid line 29 being in communication with a master hydraulic cylinder 30, which has the force piston 31 thereof operated by a foot-pedal 32 conveniently located within the craft A in its cock-pit adjacent to the pilot seat 33 within the same.

Also connected to the lever or plunger 13 is a manually operated mechanical control, which comprises a pull cable 34, trained over guide pulleys 35 and connected to a throw stick 36, within the cock-pit, as clearly shown in Figure 4 of the drawings. The bell-crank 22 is reversely set by a coiled spring 37 connected as shown in Figure 2 of the drawings. In event that the hydraulic operation of the device fails, then the pull cable 34 can be manually operated for the lock release within the engine. Both the hydraulic operation and cable operation are controlled from the cock-pit of the craft, the mechanical operation being a safety or emergency in case the hydraulic operation does not occur.

The purpose of the device constituting the present invention is to enable the draining or exhaust of any oil that may be trapped in the combustion chamber of a cylinder of the engine through the exhaust system by holding the exhaust valve free from its seat, by remote control from the cock-pit of an aircraft.

What is claimed is:

1. In an internal combustion engine of the compression type having an exhaust valve spring-pressed to a closing position, a valve rocker device for opening the valve and a push rod means for operating said valve rocker device, a mechanism for holding the exhaust valve open independently of said push rod means comprising in combination a stub shaft pivoted on the engine adjacent one end of the valve rocker and parallel to the axis thereof, a cam member secured to said shaft and adapted to engage an end of the valve rocker device to hold the same in a position to open said exhaust valve, a lever attached to said stub shaft, a bell-crank lever, means pivotally mounting the same on the engine for oscillation about an axis parallel to said stub axis, a link pivotally connected to said lever and to one end of said bell-crank lever, spring means connected to the engine and to said one end of said bell-crank lever for returning said bell-crank and lever to an initial position to cause said cam member to ride off the valve rocker device, and a cylinder, a piston slidable therein and having a piston rod, a connecting rod pivoted to the other end of said bell-crank lever and to said piston rod, a foot-operated hydraulic mechanism connected to said cylinder for actuating the piston therein, a flexible member connected to said one end of said bell-crank lever for actuating the same independently of said hydraulic mechanism.

2. In an internal combustion engine of the compression type having an exhaust valve spring-pressed to a closing position, a valve rocker device for opening the valve and a push rod means for operating said valve rocker device; a mecha-

nism for holding the exhaust valve open independently of said push rod means comprising in combination a stub shaft pivoted on the engine, a cam member secured to said stub shaft and adapted to engage the valve rocker device to hold the same in a position to open said exhaust valve, a lever attached to said stub shaft, a bell-crank lever pivoted on the engine, a link pivotally connected to said lever and to one end of said bell-crank lever, means associated with said bell-crank lever and the engine for opposing movement of said bell-crank in a direction to cause said cam member to actuate the valve rocker, a cylinder, a piston slidable therein having a piston rod, a connecting rod pivoted to the other end of said bell-crank lever and to said piston rod, and a hydraulic mechanism connected to said cylinder for actuating the piston therein.
